CAP FOR NONRIGID DISPOSABLE NURSING BOTTLES

Filed Jan. 25, 1946

UNITED STATES PATENT OFFICE

2,497,197

CAP FOR NONRIGID DISPOSABLE
NURSING BOTTLESAdda M. Allen, Arlington, Va., assignor to Dis-
posable Bottle Corporation, Washington, D. C.,
a corporation of Delaware

Application January 25, 1946, Serial No. 643,400

4 Claims. (Cl. 215—11)

1

This invention relates to a cap for a disposable bottle, and has for one of its objects the production of a simple and efficient means for detachably securing a non-rigid container to a rigid nipple-engaging cap.

A further object of this invention is the production of a simple and efficient locking means to secure the inner and outer portions of a cap together for clamping a non-rigid disposable container or bottle thereto.

Other objects and advantages of the present invention will appear throughout the following specification and claims.

In the drawing:

Figure 1 is a side elevational view of a container having the cap secured thereto;

Figure 2 is a top plan view of the cap;

Figure 3 is a bottom plan view;

Figure 4 is a fragmentary vertical sectional view taken on line 4—4 of Figure 1;

Figure 5 is a side elevational view of a modified form of the cap, showing the container secured thereto, certain parts being shown in section;

Figure 6 is a side elevational view of a further modified form of cap;

Figure 7 is a vertical sectional view of the inner portion or ring of the cap, illustrating the rubber sealing ring carried thereby;

Figure 8 is a fragmentary side elevational view of a modified form of cap, certain parts being shown in section.

By referring to the drawing, it will be seen that 10 designates the outer portion of the cap which carries a nipple-engaging portion 11 at the top thereof for detachably supporting or retaining the nipple 12 shown in dotted lines in Figure 1. The outer portion 10 of the cap is provided with a depending skirt 13 having a plurality of spaced tapering wedge-shaped lugs 14 near the lower edge of the skirt 13 and extending in a direction circumferentially of the lower edge of the skirt 13.

An inner cap portion or ring 15 fits inwardly of the outer portion 10 and is provided with a plurality of spaced bead or outwardly extending tubular socket members 16 which taper in the same direction as the tapering lugs 14 and extend substantially horizontally. These socket members 16 extend along the lower edge of the inner ring 15 in a direction circumferentially of the lower edge of the ring 15 and project sufficiently laterally of the ring to receive the tapering lugs 14 of the outer portion 13 of the cap 10 as this portion 13 is rotated on the ring 15 after the portion 13 and ring 15 are assembled in nested relation, as shown in Figures 1 and 4.

A non-rigid bottle or container 17 fits through the ring 15 and in actual use may be dropped down through this ring 15 to the position shown in Figure 4. The upper edge 18 of the container 17 is clamped over the upper edge of the ring 15 and between this ring 15 and the inner face

2

of the skirt 13 of the cap 10, as shown in Figure 4, thereby holding the non-rigid disposable container 17 firmly in engagement with the cap 10. A rubber or other gasket 19 fits over the top edge of the ring 15 and extends down the outer and inner faces of the ring 15 adjacent the upper edge thereof. This gasket 19 may be fixed in position in any desired manner or may constitute a coating of sprayed rubber or other material to provide a proper seal against which the non-rigid container 17 may fit. The container 17 may be formed of any suitable material such as Cellophane, treated paper, parchment, or material of various types which are collapsible, pliant, flexible, and inexpensive enough to be disposable after one use.

It should be understood that after the container 17 is dropped through the ring 15, the outer portion 10 of the cap is dropped over the ring 15 and the upper end of the container 17, thereby folding the upper edge of the container over the upper edge of the ring 15 in the manner shown in Figure 4. The cap 10 is placed in a position to locate the tapering lugs 14 between the sockets 16 and by rotating the outer portion 13 of the cap 10 to extend the wedge-shaped lugs 14 through the sockets 16, the outer portion 13 will be firmly clamped and wedged in a locked position upon the ring 15. In this manner the container or cup 17 will be releasably clamped in engagement with the separable sections of the cap. The cup or container 17 may be removed from engagement with the cap by merely reversing the movement above described.

In Figure 5, there is shown a modified form of the invention comprising a cap member 20 having a depending tapering skirt portion 21 which carries an annular gasket or strip of sprayed rubber or other material 22 upon the outer face thereof. The cap member 20 carries a central nipple-engaging portion and a plurality of spaced circumferentially extending socket portions or rolled flanges 23 along the upper edge thereof. A clamping ring 24 fits upwardly over the skirt portion 21 and carries a plurality of spaced tapering wedge-like lugs 25 which fit into the socket portions 23 for clamping the ring 24 in position. The ring 24 is provided with a circumferentially extending gasket of sprayed rubber or other material 26 upon its inner face for engaging the outer face of the non-rigid container 27. The upper end of the container 27 is firmly clamped between the ring 24 and the skirt 21 and the gaskets 22 and 26 provide an efficient seal.

In Figure 6, there is shown a further modified form of the invention wherein the outer portion 28 of the cap 29 is provided with spaced lugs along the lower edge of the skirt portion 31, these lugs extending in a direction circumferentially of the lower edge of the skirt portion 31. The inner ring 32, which is similar to the ring 15 shown in

Figure 4, is provided with a plurality of spaced rolled spring socket portions 33 which are provided with open upper faces. The socket portions 33 are formed of spring material and yield outwardly to permit the lugs 30 to be forced downwardly into the socket portion 33, as the outer portion 28 of the cap 29 is forced downwardly over the ring 32 to a clamped position. The container is secured to the cap in the same manner as that described with respect to the form shown in Figure 4.

The container 17 is preferably of a material to recede into the cap, as liquid is sucked from the container, in the same manner as shown in my co-pending application, relating to Nursing units with retractile container therefor, Serial Number 560,610, filed October 27, 1944 which matured as Patent No. 2,446,451, dated August 3, 1948.

It should be understood that the container may be formed of any suitable non-rigid or pliant material which may be most adaptable to the purpose for which the device is used. In Figure 8, there is shown a modified form of the invention wherein a cap member 34 is provided having a depending tapering skirt portion 35. The skirt portion 35 carries an annular gasket or strip of sprayed rubber or other material 36 upon the outer face thereof, and a similar strip 37 is carried by the inner face of the clamping ring 38. The clamping ring 38 carries lugs 39 adjacent the upper edge thereof, which lugs 39 are adapted to be gripped by the spring socket portions 40. The lugs 39, and the spring socket portions 40 shown in Figure 8, are similar to those shown in Figure 6. The container 41 is clamped between the ring 38 and the skirt 35, the strips 36 and 37 sealing the container 41 in position. This structure is especially adapted for use with the straight-wall cup wherein no flange or bead is provided upon the cup, this type of cup being shown in Figures 5 and 8.

Having described the invention, what is claimed is:

1. A cap of the class described comprising inner and outer portions, the outer portion comprising a substantially inverted cup-like member having lugs formed exteriorly thereof and extending in a line substantially parallel to the transverse axis of the cap, said inner portion having a ring-like band fitting within the outer portion and adapted to clamp a non-rigid container between the inner and outer portions, and the inner portion having sockets formed exteriorly thereof in a position to receive the lugs of the outer portion to lock the inner and outer portions together.

2. A cap of the class described comprising inner and outer portions, the outer portion comprising a substantially inverted cup-like member having lugs formed exteriorly thereof and extending in a line substantially parallel to the transverse axis of the cap, said inner portion having a ring-like band fitting within the outer portion and adapted to clamp a non-rigid container between the inner and outer portions, the inner portion having sockets formed exteriorly thereof in a position to receive the lugs of the outer portion to lock the inner and outer portions together, said lugs being arranged in spaced relation at a distance to fit between said sockets, and the lugs being adapted to be moved into said sockets when rotating the outer portion upon the inner portion.

3. A nursing device comprising a disposable container bag of collapsible, pliant flexible ma-

terial having an open forward end, a reusable rigid collar attached to the open end of said container, and a nursing nipple attached in sealing engagement to said collar, said collar being relatively narrow axially as compared with the length of said container bag, and comprising inside and outside annular members concentrically arranged with respect to one another, said inside member having an inwardly and rearwardly tapering outer sealing surface and said outside member having a correspondingly tapered inner sealing surface, said surfaces being formed to grip the open end edge area of said container bag in sealing relation between them when said end edge area is wrapped around the outer surface of said inside member and said members are axially wedged together, said members having cooperating aligned resilient lugs and sockets positioned to spring into engagement with one another when said members are axially wedged together to lock said members in their fully wedged relation to retain the open end edge area of the container bag in sealed relation between said surfaces.

4. A nursing device comprising a disposable container bag of collapsible, pliant flexible material having an open forward end, a reusable rigid collar attached to the open end of said container, and a nursing nipple attached in sealing engagement to said collar, said collar being relatively narrow axially as compared with the length of said container bag, and comprising inside and outside annular members concentrically arranged with respect to one another, said inside member having an inwardly and rearwardly tapering outer sealing surface and said outside member having a correspondingly tapered inner sealing surface, said surfaces being formed to grip the open end edge area of said container bag in sealing relation between them when said end edge area is wrapped around the outer surface of said inside member and said members are axially wedged together, said inside member having a plurality of outwardly extending resilient socket members disposed around its perimeter adjacent the forward end of its sealing surface which open toward and overlie the forward end of said outside member, said outside member having a plurality of outwardly protruding lugs thereon adjacent its forward end which are axially aligned with said sockets, said sockets and lugs being so positioned that said lugs spring into said sockets when said members are axially wedged together to lock said members in their fully wedged relation to retain the open end edge area of the container bag in sealed relation between said surfaces.
